UNITED STATES PATENT OFFICE.

WILLIAM D. TIPTON, OF TOWSON, MARYLAND.

ROTARY VALVE.

Application filed December 11, 1926. Serial No. 154,219.

The invention forming the subject matter of this application relates to an improved construction in rotary valves for internal combustion engines.

5 The object of this invention is to provide valves of this type constructed with the least number of parts which are easily assembled and provide means for automatically adjusting the valves to compensate for wear and 10 prevent leakage.

Other objects of the invention will become apparent as the detailed description proceeds.

In the drawings:—

15 Fig. 1 is an elevation of a two-cycle rotary valved internal combustion engine, with parts thereof broken away to disclose the valve mechanism clearly;

20 Fig. 2 is a transverse vertical section taken on the line 2—2 of Fig. 1;

Fig. 3 is a central vertical section to an enlarged scale of a diaphragm construction forming the essential parts of the rotary valve disclosed herein;

25 Fig. 4 is a central vertical section through a cylinder and cooperating rotary valve of a four-cycle internal combustion engine equipped with this invention;

30 Fig. 5 is a perspective view of the valve used in the type of engine shown in Fig. 4;

Fig. 6 is a perspective view of one-half of one of the valve elements;

Figure 6^a is a fragmentary detail of the valve structure shown in Figures 4, 5, and 6.

35 Fig. 7 is a central transverse section of a modified form of the invention;

Fig. 8 is a central vertical section through a modified form of the two-cycle valve;

40 Fig. 9 is a central vertical section through the diaphragm supporting arms of another modification of the two-cycle valve;

Fig. 10 is a central vertical section through a modification of the four-cycle valve; and

45 Fig. 11 another modification of the four-cycle valve.

As the invention disclosed herein resides primarily in the rotary valve construction, the details of the engine are not illustrated nor described herein. In Fig. 1 of the draw-

ing the engine block 1, shown as provided 50 with four cylinders 2, is bored lengthwise to form a cylindrical valve chamber 3 in which the valves 4 are mounted to rotate. The valves 4 are properly spaced angularly relative to each other and are interlocked as by 55 tongue and groove connections to be rotated together by any suitable means connected operatively to the gear 6.

Each valve comprises a semi-cylindrical section 7 having diametrically opposed rectangular recesses 8 and 9 formed in its straight edges 10 and 11, to coincide with similar recesses 12 and 13 formed in the straight edges 14 and 15 of the other section 16. The two sections 7 and 16 when joined 65 together, as shown in Fig. 2, fit snugly and rotatably in the chamber 3 and are connected yieldingly to each other by the diaphragm structure shown in Figs. 1, 2 and 3.

The section 7 has an aperture 17 formed in 70 the center of its cylindrical surface and an arm 18 has a shouldered end 19 screwthreaded into said aperture 17 or is otherwise fixed to extend radially toward the axis of the cylindrical valve 4 where it is spread out to form 75 a plane circular seat 20 for a circular diaphragm 21.

The diaphragm 21 is punched out at its center to form an aperture 22, and is bent around this aperture to form a frusto-conical 80 seat or counter-sink 23 for the head 24 of a screw 25. The arm 18 is axially bored throughout its length and has the inner end of the bore 26 screw-threaded to receive the corresponding screw threads of the screw 25, 85 which is also provided with a bore 27 coaxial with the bore 26.

The diaphragm 21 is secured to the arm 18 at the center of the circular seat 20 by the screw 25 only and is not otherwise secured to 90 the seat 20.

An arm 28 similar in every respect to arm 18 is similarly secured to the valve section 16 by having its shouldered end 29 fixed suitably in the aperture 17' and is spread out at its inner end to form the circular seat 30 for the diaphragm 31 similar in every respect to diaphragm 20 and secured to the arm 28 by a

screw 32 having a bore 33 coaxial with bore 27 and the bore 34 formed in arm 28.

Adjacent their center edges the diaphragms 21 and 31 are stamped to form annular crimps 35 and 36 respectively. The flat parts 37 and 38 have an annular spacer 39 arranged between them and the diaphragms are secured to each other at their outer circular edges by a channeled ring member 40 which clamps these flat parts 37 and 38 securely to the spacer 39. The structural details of this member 40 are not described herein, since any other suitable clamping means may be employed to fix the diaphragms to the ring 39 and make a strong 15 gas-tight fit therewith.

The ports formed in each valve by the recesses 8-12 and 9-13 are of the same area as the cylinder inlet ports 41, and the valve chamber 3 is provided with recesses 41' of the 20 same area as ports 41.

The engine block 1 is provided with the usual gas inlet port 42, the exhaust ports 43 and screw-threaded apertures 44 adapted to receive the usual spark plugs 45.

25 The diaphragms 21 and 31 are fixed at their centers only to the arms 18 and 28 and are formed so that they normally tend to separate said arms so as to force the cylindrical sections 7 and 16 of the rotary valve into close rotary fit against the cylindrical wall of valve chamber 3. This condition of the valve is shown in Fig. 2, where the valve is positioned to permit the flow of gas into the cylinder 2, at the intake-exhaust stroke of the piston.

35 When the valve is rotated at ninety degrees to the position shown in Fig. 2, the exhaust ports 43 are closed and the piston is on its compression-firing stroke. The compressed gas passes through the bores 26-27 or 33-34, as 40 the case may be, and in between the two diaphragms 21 and 31 to cause them to separate still further and thereby, through arms 18 and 28, to force the valve sections 7 and 16 into still closer contact with the wall of chamber 3. The recesses 41' then serve to balance the 45 pressures on opposite sides of the valve.

It will be obvious that when the valve is positioned at the compression stroke of the piston, the parts thereof will be separated 50 under a force directly proportional to the compression in the cylinder.

55 Figs. 4, 5, and 6 illustrate the application of this invention to a four-cycle engine. Here the valve 45 is split lengthwise and its two halves 46 and 47 are secured to each other by diaphragms 48 and 49 secured to each other and to their respective halves 46 and 47 by a split ring 49' in substantially the same manner as that illustrated in Figs. 1, 2, and 3.

60 In this form of the invention the gas inlet 50 is aligned with the outlet 51; and in order to prevent exhaust gases passing backward through the bore 52, when the valve is in the position shown in Fig. 4, to the inlet 50, an

arcuate strap 53 of a width sufficient to close 65 said bore 52 is suitably fixed in the inlet 50 and in contact with said valve.

Another modification of this invention is shown in Fig. 7. In this form, the valve is split into halves 54 and 55 and these halves 70 are provided at their centers with cylindrical recesses 56 and 57 respectively. The recess 56 serves as a seat for the correspondingly shaped projection 58 formed centrally on the cylinder 59 which extends with a sliding fit 75 across both halves 54 and 55 in suitably boxed out parts (not shown) in said halves.

A piston 60 having a dished head 61 fits 80 slidably within said cylinder 59 and has a projection 62 seated in the recess 57. An annular recess 63 is formed in the head 61 and a coil spring 64 seated in this recess tends to 85 separate the cylinder and piston and normally keep the valve halves 54 and 55 in close rotary fit in the valve chamber. A bore 65 extending transversely through the valve halves cylinder and piston serves to admit gas when the valve is in its compression position, and thereby to force the valve halves into gas tight contact with the wall of the valve chamber. It 90 will be obvious that gas under compression entering the bore 65 will pass between the dished head 61 and the adjacent flat head of the cylinder 59 and will force these members apart in direct proportion to the force of gas compression. 95

It will be noted that in all forms of the invention the valves are split in halves, and means are interposed between these halves to keep them normally in spring contact with the valve chamber wall; and, in addition to this means, the valve mechanism is so constructed as to utilize the compression of the gas to increase the contact pressure of the valves with the wall of the valve chamber. For efficient 100 operation of this type of valve, the effective pressure area of the diaphragms, or their equivalent shown in Fig. 7, should be about twice the area of the port opening into the cylinder. 105

In the modification shown in Fig. 8 the diaphragms 66 and 67 have their peripheries bent over the circular seat flanges 21' and 30' extending from the arms 18' and 28' respectively, and are fixed to said flanges at their outer edges by means of the rings 68 and 69, respectively, which may be shrunk or welded on, or otherwise suitably secured to said flanges. 115

These diaphragms are arranged to contact 120 normally at their centers and to keep the valve sections 17' and 18 normally in close fit with the cylindrical wall of the valve chamber.

In the modification shown in Fig. 9 a single diaphragm 70 is used to separate the two halves of the valve, of which the supporting arms 18' and 28' only are shown. The dia- 125

phragm 70 has its center punched and countersunk to be secured at its center to the arm 28' by a screw 25' and has its periphery secured to the outer edge of flange 21' by a 5 ring 68.

The arms 18' and 28' are provided with the bores 26' and 34' and the screw 24' with the bore 33'. The operation of this form of the invention and of that shown in Fig. 8, will 10 be obvious from inspection of the drawing and from the description of the preceding forms of the invention.

In the modification shown in Fig. 10, the valve comprises a central body 71 and similar segments 72 arranged one on each side of said body 71. Each segment similarly dished on its flat face and has a central bore 73 therethrough, and a diaphragm 74 is secured in any suitable manner at its outer periphery 20 to the flat face of the segment over the dished part thereof. As usual the diaphragms are slightly bowed to contact at their centers with the flat faces of body 71, and normally tend to separate segments 72 from body 71 to ensure a snug fit of the valve in its chamber.

In the modification illustrated in Fig. 11, the valve body 75 is axially bored to receive the cylindrical members 76 each of which is provided with axial bores 77 screwthreaded 30 at the inner flat end 78 to receive the axially bored screw 79. The bore 77 is countersunk to receive the countersunk center of the diaphragm 80 and the head of screw 79. The two diaphragms 80 are spaced apart at their 35 peripheries and are clamped together by a ring 81 substantially in the same manner as shown in Fig. 4. As will be obvious from the drawing, the diaphragms in this modification are wholly concealed in the valve body 75.

40 The operation of the modification shown in Figs. 10 and 11 is substantially as in the previously described form of the invention.

I claim:

1. The combination with a cylindrical 45 valve chamber of a cylindrical valve rotatable therein, said valve being formed of two similar halves, and means between said halves to force them into yielding contact with the wall of said chamber.

2. The combination with a cylindrical valve chamber of a cylindrical valve rotatable therein, said valve being formed of two halves similar in every respect, and spring mechanism interposed between said halves to 55 force them into yielding rotary contact with the wall of said chamber.

3. The combination with a cylindrical valve chamber of a cylindrical valve rotatable therein, said valve being formed of two halves similar in every respect, a circular 60 spring diaphragm having its center fixed to each half at the center thereof, and means for securing the circular edges of said diaphragms to each other, said diaphragms being shaped to effect separation of said halves

and to force them into yielding contact with the wall of said chamber.

4. In an internal combustion engine, the combination with a cylinder a cylindrical valve chamber having a port communicating 70 with said cylinder, a cylindrical valve rotatable in said chamber, said valve comprising two segments slightly spaced apart, yielding means interposed between said segments to force them normally into contact with the 75 wall of said chamber, said segments and means being provided with alined bores to permit gas from said cylinder to enter the space between said segments when said bores register with said port.

5. In combination with a cylinder, a cylindrical valve chamber having a port communicating with said cylinder, a cylindrical valve rotatable in said chamber said valve being divided into two parts, a pair of circular 85 spring diaphragms fixed at their center to each part and having their circular edges spaced apart from and fixed to each other, said parts and diaphragms being provided with alined bores to permit gas to enter the 90 space between said diaphragms when the said bores communicate with said port.

6. In combination with a cylinder, a cylindrical valve chamber having a port communicating with said cylinder, a cylindrical valve 95 rotatable in said chamber, said valve comprising two similar parts, yielding means interposed between said parts to keep them normally spaced apart and in contact with the wall of said chamber, said parts and means being provided with alined bores to permit gas from said cylinder to enter the space between said parts when the bores communicate with said port, said chamber having a recess of the same cross-sectional area as 100 said port to provide for balance of gas pressure on the valve parts when said bores communicate with said port.

7. The combination with an engine cylinder having a valve seat and a port between 110 said seat and cylinder, a valve controlling said port, said valve including two parts, and means interposed between said parts and adapted to be exposed to the internal pressure in the cylinder to move said parts to 115 contact tightly with said seat.

8. The combination with an engine cylinder having a bore forming a valve seat, a valve fitting rotatably in said seat and comprising two parts, a pair of spaced apart diaphragms connected at their edges to each other and to said parts at their centers, said diaphragms and parts being bored to expose the adjacent faces of said diaphragms to internal pressure in cylinder to force said parts into tight contact with said seat.

9. The combination with an engine cylinder having a valve seat and a port between 120 said seat and cylinder, a valve controlling said port, said valve including two parts,

and means including a spring diaphragm interposed between said parts and adapted to be exposed to the internal pressure in the cylinder to move said parts to contact tightly with said seat.

5. 10. The combination with an engine cylinder having a bore forming a valve seat, a valve fitting rotatably in said seat and com-

prising a central body, a pair of similar segments disposed at opposite sides of said body and having bores through the center thereof, and diaphragms secured to said segment and normally engaged in said body to force said segments against said seat. 10

In testimony whereof I affix my signature.
WILLIAM D. TIPTON.
